UNITED STATES PATENT OFFICE

STEWART L. CAMPBELL, OF BERKELEY, CALIFORNIA, ASSIGNOR TO JOHN GRANT, OF LOS ANGELES, CALIFORNIA

EXPANDING DRILL OR REAMER

Application filed February 14, 1928. Serial No. 254,241.

This invention has relation to collapsible and expandable drilling tools, and although the invention is peculiarly applicable to a drill bit of the fish-tail or similar type, and will be explained particularly with regard thereto, it is also applicable generally to expandable reamers, as will be pointed out.

A general object of the invention is the provision of a simple and strong expandible construction for a drilling tool of the type that utilizes a cutting element in the form of a flat blade typically such as the blade of a fish-tail bit. In the ordinary non-expandible fish-tail bit this blade is usually one single piece, but according to my invention I divide the blade into two parts or half blades which are then so mounted as to be relatively rotatable about a common center and preferably relatively rotatable about the vertical center of the tool. And preferably one of the half blades, or cutting elements as I shall call them, may be formed integrally with the tool body, the relative swinging motion taking place by virtue of swinging movement of the other cutting element or blade about the body center.

How the invention is carried out in a practical design and how it may be made applicable to reamers, etc., will be best understood from the following detailed description. It will be understood that this description is intended only to set out in particular detail a present preferred and illustrative embodiment of the invention and is not to be taken as a limitation upon the invention except as expressly so stated in the appended claims.

For the purposes of description I refer to the accompanying drawings in which

Figure 1 is a side elevation of an expansive fish-tail bit showing the tool in its expanded position.

Figure 2 is a central vertical section taken in the same aspect as Figure 1.

Figure 3 is a view similar to Figure 1, but showing a simple modification adapting the tool to use as a reamer.

Figure 4 is a bottom view of the tool shown in Figure 1.

Figure 5 is a similar bottom view showing the tool in contracted condition.

Figure 6 is a cross-section on line 6—6 of Figure 1.

Figure 7 is a similar cross-section showing the tool contracted.

Figure 8 is a cross section on the line 8—8 of Figure 1.

Figure 9 is a similar cross section showing the tool contracted.

Figure 10 is an edge view of the tool shown in Figure 1.

In the drawings I show a suitable body at 10 and a cutting element 11, in the form of a half fish-tail blade, formed integrally or connected integrally at its upper end with body 10. The formation and contour of element 11 may be designed to suit any particular type of work. I show the element substantially in a form corresponding to one-half of the usual fish-tail blade except that the inner or central edge of the half blade 11 is provided with certain recesses and projections to be hereinafter described.

The other half of the fish-tail blade is formed by the relatively movable cutting element 12 which is shown as being substantially similar to element 11 in contour and shape, so that when the two half blades 11 and 12 are assembled in their expanded relative positions they form in effect the whole fish-tail bit. The half blade or element 12, however, is not made integral with body 10, but is mounted with respect to that body and with respect to element 11 so that it may swing between the relative positions shown in Figures 4 and 5.

To provide a pivot on which element 12 may swing I preferably provide a central pivot mandrel 13 which is formed integrally with and depends from a sub 14. This sub has the usual taper-threaded pin 15 at its upper end for connection with a drill stem and at its lower end and at the upper end of the pivot mandrel 13 it has another taper-threaded pin 16 which screws into a corresponding taper-threaded socket in the upper end of the body.

The two adjacent inner edges of elements 11 and 12 are formed with inter-engaging extensions and notches 20 and 21 as will best be seen from an inspection of Figure 2.

These extensions 20 form in effect hinge eyes, and the pivot mandrel 13 extends down through the parts 20 to form in effect the hinge pin between the two parts 11 and 12 and to form a pivot upon which the part 12 swings. In the particular design here shown the element 12 has two such extensions or hinge eyes 20 spaced vertically from each other, while the element 11 has but one such extension or hinge eye 20 located between the two extensions 20 of element 12. The pivot mandrel 13 may be stepped down in diameter as it passes downwardly through the successive extensions 20, so that the exterior diameters of these extensions may be correspondingly decreased, as is indicated in Figures 1 and 10. This arrangement of decreasing diameters makes an assembly in which there is no abrupt or large increase in diameter at any point under the body, thus minimizing the liability of the tool becoming clogged or balled up with mud. This feature of the design will be well understood from the edge elevation of Figure 10.

25 The support afforded the lower end of the pivot mandrel 13 where it passes through the extension 20 of element 11 greatly strengthens the pivot mandrel and prevents its breakage or distortion. The two spaced bearings 30 of element 12 upon the pivot mandrel give that element a comparatively long vertical extent of bearing and insure its rigid support against any forces tending to twist it out of proper vertical alinement.

35 In order to limit the relative swinging movement of element 12 suitable stops are provided. These stops may be provided in a variety of manners, but I prefer here to show such stops applied to the upper end of element 12 and also applied to points near its lower end. Thus, at its upper end the element 12 may have a stop lug 25, in the form of a sector as is most clearly shown in Figures 8 and 9. This sector plays in a recess 26 which is cut or otherwise formed in the lower surface of body 10 and is here shown as semi-circular in extent. The radial shoulders 27 and 28 at the ends of recess 26 form the stops against which sector 25 brings up when element 12 reaches its limiting positions. Thus, as shown in Figure 8, where the stop sector 25 is up against shoulder 27, the two elements 11 and 12 extend diametrically opposite each other and form in effect a complete fish-tail blade. By relative rotation of element 12 to the position of Figure 9 the stop sector 25 is brought up against shoulder 28, with the elements 11 and 12 then in the relative positions shown in Figures 5, 7 and 9. Right handed rotation of the tool, looking down upon it, will, by reason of the drag upon element 12, cause that element to move to its expanded position shown in Figures 4, 6 and 8; while left-handed rotation of the

tool likewise will cause that element to move to its contracted position shown in Figures 5, 7 and 9. In the expanded position, with the two blade elements 11 and 12 opposite each other, the size of the hole which is cut is indicated by the circle denoted H in Figure 4. With the elements 11 and 12 in the relative positions shown in Figure 5 the tool then can pass through a hole, or through a casing, of interior diameter less than the diameter of circle H, because the body of the tool, which is smaller in diameter than circle H, can then bear directly against one side of the hole or casing and the two projecting cutter elements 11 and 12 are both located at or near the opposite side of the hole or casing. Thus, in Figure 5 the circle at C indicates the interior size of a casing through which the collapsed tool may be passed; and the circle H is again shown for comparison with circle C.

Additional stops for the swinging motion of element 12 may be provided near its lower end. Thus, the lowermost extension or hinge eye 20 of element 12 may carry a stop extension 30 which, in the expanded position shown in Figure 6, brings up against element 11; and furthermore element 12 may have still another stop near its lower end in the form of a stop lug 31 which swings around against the face of element 11 when the parts are in expanded position. This is best shown in Figures 4 and 5.

I have now described the invention particularly as an expansive and contractive fish-tail bit, but by reference to Figure 3 the adaptability of the invention to use as a reamer or the like will be readily understood. In fact the only essential difference between the tool as a fish-tail bit and the tool as a reamer is in this, that when used as a drilling bit it has its cutting edges, or at least its major cutting edges, at the lower ends of the cutting element (in the form shown in Figure 1 these cutting edges will usually be merely sharp edges along the lower ends of elements 11 and 12) while in the reamer form the cutting edges are placed along the lateral vertical edges of the elements 11 and 12. Thus the form of Figure 1 may be readily made into a reamer suitable for certain kinds of formation merely by sharpening the outer vertical edges of elements 11 and 12. But in Figure 3 I show those outer vertical edges equipped with roller reaming cutters 35 adapted particularly for reaming operations to ream out a hole which has already been drilled either by another tool or by the same tool, and the tool here described may lend itself very readily to performing simultaneously the drilling and reaming operations, the lower sharpened edges 36 of elements 11 and 12, or 11^a and 12^a of Figure 3, drilling a hole of a certain size ahead of the reaming

cutters 35, and the reaming cutters 35 then reaming the hole out to the desired larger diameter.

It will therefore be recognized that the elements 11 and 12 may either be the actual cutters themselves, or may be carriers for the actual or ultimate cutters; and this will be understood when I refer to the parts 11 and 12 as being cutting elements.

10 Expansive and contractive movement of the parts of this expansive tool may be wholly or partially accomplished by relative rotations as above described. However, longitudinal movement of the tool up against the 15 lower end of the casing may either act solely to cause contractive movement or may act in conjunction with left-handed rotation to cause contractive movement. For this purpose the upper corners of elements 11 and 12 20 may be beveled as shown at 40 so that when the tool is drawn up against the lower end of the casing, and as soon as element 12 has moved slightly from its fully expanded position, then the pressure of the casing end upon 25 the beveled face 40 will tend to swing element 12 around toward element 11—in other words, will tend to swing the two elements around toward each other.

around toward each other. The sub 14 and pivot mandrel 13 may be provided with a central water course 50 to deliver circulating fluid to the lower end of the pivot mandrel. This lower end is located at the lowermost hinge lug 20 and is thus located fairly close to the lower cutting edges of elements 11 and 12. The water or other fluid delivered through the passage 50 will thus be delivered centrally of the two elements 11 and 12 and near their lower ends and directly into the slight gap 51 between their adjacent inner edges.

I claim:

1. In an expansive tool of the character described, a substantially cylindric body, a cutting element integral with the body and lying substantially in a plane radial to the central vertical axis of the body, a central pivot mandrel extending down through and below the body and screw-threadedly mounted therein, the inner edge of said cutting element 45 having a bearing lug through which the lower part of the pivot mandrel passes and by which it is supported, another cutting element lying substantially in a plane radial to said central vertical axis and having spaced bearing lugs surrounding the pivot mandrel, whereby said last mentioned cutting element is swingingly supported upon the pivot mandrel to swing about the central vertical axis 50 of the body.

55

60

65 2. In an expansive tool of the character described, a substantially cylindric body, a cutting element integral with the body and lying substantially in a plane radial to the central vertical axis of the body, a central pivot man-

drel extending down through and below the body and screw-threadedly mounted therein, the inner edge of said cutting element having a bearing lug through which the lower part of the pivot mandrel passes and by which it is supported, another cutting element lying substantially in a plane radial to said central vertical axis and having spaced bearing lugs surrounding the pivot mandrel, whereby said last mentioned cutting element is swingingly supported upon the pivot mandrel to swing about the central vertical axis of the body, the outer edges of both cutting elements extending horizontally beyond the exterior surface of the body.

3. In an expansive tool of the character described, a substantially cylindric body, a cutting element integral with the body and lying substantially in a plane radial to the central vertical axis of the body, a central pivot mandrel extending down through and below the body and screw-threadedly mounted therein, the inner edge of said cutting element having a bearing lug through which the lower part of the pivot mandrel passes and by which it is supported, another cutting element lying substantially in a plane radial to said central vertical axis and having spaced bearing lugs surrounding the pivot mandrel, whereby said last mentioned cutting element is swingingly supported upon the pivot mandrel to swing about the central vertical axis of the body, a stop lug mounted on the upper end of the last mentioned cutting element, and the body having a lug receiving recess of limited extent to allow limited swinging movement of said stop lug and of the swinging cutting element.

4. In an expansive tool of the character described, a central vertical pivot mandrel, a pair of cutting elements mounted on said pivot mandrel, and standing substantially in planes radial to its vertical center, one of said elements being relatively rotatable about the center of the pivot mandrel between a position diametrically opposed to the other element and a position in which both elements are at one side of the pivot mandrel.

5. In an expansive tool of the character described, a central vertical pivot mandrel, 115 a pair of cutting elements mounted on said pivot mandrel, and standing substantially in planes radial to its vertical center, one of said elements being relatively rotatable about the center of the pivot mandrel, and stop means to limit said relative rotation between 120 positions in which said elements stand substantially diametrically opposite each other and positions in which said elements stand both at the same side of the pivot mandrel. 125

6. In an expansive tool of the character described, a central vertical pivot mandrel, a pair of cutting elements mounted on said pivot mandrel, and standing substantially in 130

planes radial to its vertical center, one of said elements being relatively rotatable about the center of the pivot mandrel between a position diametrically opposed to the other element and a position in which both elements are at one side of the pivot mandrel, said cutting elements extending below the lower end of the pivot mandrel, and the pivot mandrel having a central vertical circulation passage 10 adapted to deliver fluid from its lower end centrally between the lower ends of the two elements.

7. In an expansive tool of the character described, a substantially cylindric body, a cutting element integral with the body, depending therefrom, and lying substantially in a plane radial to the central vertical axis of the body, a central pivot mandrel extending down through and below the body and 15 non-rotatively mounted in the body, another cutting element lying substantially in a plane radial to said central vertical axis and swingingly mounted at its inner edge on the pivot mandrel, whereby said last mentioned cutting element is swingingly supported upon the pivot mandrel to swing about the central vertical axis of the body.

8. In an expansive tool of the character described, a substantially cylindric body, a cutting element integral with the body, depending therefrom, and lying substantially in a plane radial to the central vertical axis of the body, a central pivot mandrel extending down through and below the body and 20 non-rotatively mounted in the body, the lower part of the pivot mandrel having a support bearing on the inner part of said cutting element, another cutting element lying substantially in a plane radial to said central vertical axis and swingingly mounted at its inner edge on the pivot mandrel, whereby said last mentioned cutting element is swingingly supported upon the pivot mandrel to swing about the central vertical axis of the body.

45 9. In an expansive tool of the character described, a substantially cylindric body, a cutting element integral with the body, depending therefrom, and lying substantially in a plane radial to the central vertical axis of the body, a central pivot mandrel extending down through and below the body and non-rotatively mounted in the body, another cutting element lying substantially in a plane 50 radial to said central vertical axis and swingingly mounted at its inner edge on the pivot mandrel, whereby said last mentioned cutting element is swingingly supported upon the pivot mandrel to swing about the central vertical axis of the body, and stops limiting the swinging movement of the second mentioned cutting element between a position substantially diametrically opposed to the 55 first mentioned cutting element and a position

tion in which both cutting elements are at one side of the pivot mandrel.

In witness that I claim the foregoing I have hereunto subscribed my name this 27 day of January, 1928.

STEWART L. CAMPBELL.
